DESIGN.

H. R. HANSEN.

EMBLEM,

APPLICATION FILED OCT. 17, 1914.

48,519.

Patented Feb. 8, 1916.

Inventor:
Henry R. Hansen
By his Attorney
Carl P. Hansen.

UNITED STATES PATENT OFFICE.

HENRY R. HANSEN, OF JERSEY CITY, NEW JERSEY.

DESIGN FOR AN EMBLEM.

48,519.

Specification for Design.

Patented Feb. 8, 1916.

Application filed October 17, 1914. Serial No. 867,256. Term of patent 3½ years.

To all whom it may concern:

Be it known that I, HENRY R. HANSEN, a citizen of the United States of America, residing at Jersey City, in the county of Hudson and State of New Jersey, have invented a new, original, and ornamental Design for Emblems, of which the following is a specification, reference being had to the accompanying drawing, forming part thereof.

The figure is a front view of an emblem showing my design.

I claim:

The ornamental design for an emblem, as shown.

HENRY R. HANSEN.

Witnesses:

JOHN SCHWARZ,
D. LEWIS MATTERN.
